UNITED STATES PATENT OFFICE.

ROBERT C. WADE, OF MALDEN, MISSOURI.

SECTIONAL SMOKE-BURNER.

1,033,134.

Specification of Letters Patent. Patented July 23, 1912.

Application filed April 20, 1911. Serial No. 622,336.

To all whom it may concern:

Be it known that I, ROBERT C. WADE, a citizen of the United States, residing at Malden, in the county of Dunklin and State 5 of Missouri, have invented a new and useful Sectional Smoke-Burner, of which the following is a specification.

It is the object of the present invention to provide a device adapted to be mounted in 10 a furnace of standard construction, to effect a thorough consuming of the smoke generated in such furnace.

Specifically, it is the object of the invention to provide a device of the character 15 above mentioned, which will divide the volume of smoke, and introduce into the divided volume of smoke, quantities of heated air, thereby effecting a thorough consuming of the smoke, thus effecting the double end 20 of preventing the delivery into the atmosphere, of a dense volume of smoke, and of consuming, to a useful purpose, the combustible material carried in suspension in the smoke.

25 With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

35 In the accompanying drawings,—Figure 1 is a longitudinal section; Fig. 2 is a transverse section upon the line A—B of Fig. 1; Fig. 3 is a transverse section on the line C—D of Fig. 1; and Fig. 4 is a perspective 40 of one of the draft boxes.

In the drawings, the numeral 1 designates generally, a furnace of any desired shape and proportions.

The numeral 2 designates the grate of the 45 furnace, the numeral 3 denotes the stoke door, and the numeral 4 denotes the ash door.

Projecting forwardly from the rear wall of the furnace 1, is a platform 5. Rising 50 from the grate 2, and terminating at its upper edge in the vicinity of the platform 5, is a partition 6. Supported upon the platform 5 and above the partition 6, are a plurality of spaced boxes, denoted by the 55 numerals 7, 8, 9, and 10, the boxes being of identical construction. The top member 11

which is superposed upon the box 10, differs slightly in construction from the boxes proper, and this member 11 will be described in detail hereinafter. Each of the 60 boxes, then, comprises a bottom 12, side walls 14, and end walls 15, which extend but part way across the ends of the box. Each box further includes a top plate 16 and another top plate 17, the top plate 17 being 65 broader than the top plate 16, and being disposed adjacent the rear of the furnace. Projecting inwardly from the ends of the walls 15, are longitudinally extended deflectors 18, the ends of which are spaced 70 apart. Extended transversely of the box, and terminally united with the side walls 14, is a transverse partition 19, located between the free ends of the deflectors 18. Each box supports near its ends and at the side of the 75 furnace an I beam 20. Each box supports, in its intermediate portion, and aligned vertically with the transverse partition 19, another I beam 21. Thus, the several superposed boxes are supported one upon the 80 other.

Applied to the faces of the side walls of the furnace 1, are upright flues 22, the upper ends of which are closed, the lower ends of the flues 22 being open. In the side walls 85 of the furnace 1, at the bottom of the flues 22, there are openings 23. The member 11 forms the uppermost portion of the structure, and is provided with a raised, longitudinal rib 25. The stack portion of the 90 structure is shown at 26.

In operation, the products of combustion pass between the boxes, and out of the stack 26. The air enters the flues 22 at their 95 lower ends, and passes into the ends of the boxes, the air being raised in temperature, to a high point, by reason of the fact that the products of combustion pass between the boxes and heat the bottoms 12 thereof. The air encounters the deflectors 18 and the partitions 19 successively, and finally passes through the opening between the top plates 16 and 17, to mingle with the products of combustion. By this operation, heated air 100 will be supplied to the products of combustion, during the passage between the boxes, this air introduced from the exterior of the furnace, being well supplied with oxygen. Thus, a thorough combustion of the disintended particles in the smoke is effected, the 110 smoke being thus burned clean, and a waste of fuel being avoided.

Owing to the fact that it will be somewhat difficult to maintain a fire beneath the bottom 12 of the lowermost box, if the fuel is introduced through the stoke door 3, a fire may be maintained beneath the bottom 5 of the lowermost box by introducing combustible material through an auxiliary stoke door 30.

The platform 5, obviously tends to prevent a draft beneath the boxes, into the stack 26, the platform 5 compelling the products of combustion to pass between the boxes, as hereinbefore described. The door denoted by the numeral 31, serves as a clean-out for that portion of the structure which is to the rear of the boxes. The partition 6 prevents the fire which is built through the door 30 from being choked by ashes from the fire which is to the front of the partition 6.

The boxes preferably, although not necessarily, are fashioned from cast iron, and it will be seen that the construction of the entire device is such, that these boxes may readily expand and contract, without endangering a breakage of any of them. The mounting of the boxes upon the platform 5, obviously, is such that the platform in no wise interferes with the transverse expansion of the boxes.

Having thus described the invention, what is claimed is:—

1. In a device of the class described, a furnace having openings in its side walls, flues communicating with the openings at their lower ends; superposed, spaced boxes located within the furnace and forming smoke passage-ways therebetween, said boxes having openings in their end walls communicating with the flues, each box being closed at its bottom and along its sides and open at its top only, there being deflectors in the boxes, adapted to secure a thorough admixture of the air passing inwardly 45 into the boxes, through the flues, with the smoke which passes between the boxes.

2. In a device of the class described, a furnace; a grate therein; a partition disposed transversely of the furnace above the grate and dividing the fire upon the grate;

a platform horizontally disposed in the furnace and extended inwardly from the rear wall thereof to overhang the partition; a box supported upon the platform; an auxiliary stoke door in the furnace, to the rear of the partition, permitting the building of a separate fire to the rear of the partition; other boxes superposed upon the first named box, all of the boxes being closed at the bottom and open at the top, the boxes being spaced apart to form smoke passage-ways therebetween; and means for supplying air through the ends of the boxes, to mix with the smoke which passes between the boxes from in front of the partition.

3. In a device of the class described, a furnace provided with upright flues upon its sides, the flues being open at the bottom; superposed boxes supported within the furnace and spaced to form smoke passages therebetween, each box having openings in opposite ends communicating with the flues; each box having inwardly projecting, longitudinal deflectors located adjacent the openings in the said boxes; a transverse partition located between the ends of the deflectors; the boxes being closed at their bottoms and at their sides, each box having top plates spaced apart adjacent the longitudinal center of the box, between which plates air is fed into the smoke passages.

4. As an article of manufacture, a box adapted to be employed in the construction of a smoke consumer, the said box consisting of a bottom, side walls, top plates extended inwardly from the side walls and spaced apart adjacent the longitudinal center of the box, end walls extended part way across the ends of the box, deflectors located at the ends of the end walls, and projecting inwardly into the box; and a transverse partition uniting the side walls, and located between the inner ends of the deflectors.

In testimony that I claim the foregoing as my own, I have hereto affixed my signature in the presence of two witnesses.

ROBERT C. WADE.
